CLAIM

An ornamental design for a bottle with cap, as shown and described.

DESCRIPTION

FIG. 1 is a perspective view of a first embodiment of our new design for a bottle with cap

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top view thereof;

FIG. 7 is a bottom view thereof; and

FIG. 8 is a bottom-rear perspective view thereof.

FIG. 9 is a perspective view of a second embodiment of our new design for a bottle with cap

FIG. 10 is a front elevational view thereof;

FIG. 11 is a rear elevational view thereof;

FIG. 12 is a right-side elevational view thereof;

FIG. 13 is a left-side elevational view thereof;

FIG. 14 is a top view thereof;

FIG. 15 is a bottom view thereof; and

FIG. 16 is a bottom-rear perspective view thereof.

FIG. 17 is a perspective view of a third embodiment of our new design for a bottle with cap

FIG. 18 is a front elevational view thereof;

FIG. 19 is a rear elevational view thereof;

FIG. 20 is a right-side elevational view thereof;

FIG. 21 is a left-side elevational view thereof;

FIG. 22 is a top view thereof;

FIG. 23 is a bottom view thereof; and,

FIG. 24 is a bottom-rear perspective view thereof.

(Continued)

The dot-dash broken lines in the drawings define the bounds of the claim. Those boundary lines and the unshaded area within form no part of the claimed design.
